US0D1104142S

(12) **United States Design Patent** (10) Patent No.: **US D1,104,142 S**
(45) Date of Patent: ** Dec. 2, 2025

(54) **CUTTING PLOTTER**

(71) Applicant: **GRAPHTECH CORPORATION**,
Kanagawa (JP)

(72) Inventors: **Takahisa Umezawa**, Yokohama (JP);
Hiroshi Ohtsuka, Yokohama (JP)

(73) Assignee: **GRAPHTECH CORPORATION**,
Kanagawa (JP)

(**) Term: **15 Years**

(21) Appl. No.: **29/953,934**

(22) Filed: **Jul. 24, 2024**

(30) **Foreign Application Priority Data**
